UNITED STATES PATENT OFFICE.

DANIEL C. MULVIGHILL, OF HANNIBAL, MISSOURI.

MOLD-FORMING APPARATUS.

1,325,750.

Specification of Letters Patent. Patented Dec. 23, 1919.

Application filed June 23, 1919. Serial No. 306,050.

To all whom it may concern:

Be it known that I, DANIEL C. MULVIGHILL, a citizen of the United States of America, and resident of Hannibal, county of Marion, 5 and State of Missouri, have invented certain new and useful Improvements in Mold-Forming Apparatus, of which the following is a specification, and which are illustrated in the accompanying drawings, forming a 10 part thereof.

The object of the invention is the provision of means whereby molds may be formed and separated from the pattern more readily and efficiently and with less 15 damage to the mold than heretofore.

In the accompanying drawings;

Figure 1 is a side view,

Fig. 2 is an end view of an old form of jolting machine supporting a mold forming 20 apparatus embodying the invention,

Fig. 3 is a plan view of the stripping plate with the stripping ring in place but with the pattern removed,

Fig. 4 is a central vertical section showing 25 the drag in place on the ring,

Fig. 5 is a similar section showing the molding of the cope and with the mold separated from the pattern;

Fig. 6 is a bottom plan view of a weighted 30 rammer utilized in conjunction with the cope,

Fig. 7 is a perspective view of a gate forming implement,

Fig. 8 is a plan view, and

Fig. 9 is a section taken on the line 9—9 35 of Fig. 8, of a flask locked up but with a portion of the sand removed to show details.

The invention is preferably utilized in 40 connection with what is known as "machine" molding and any known form of jolting machine may be employed, as that illustrated in Fig. 1, in which 10 indicates the table having an annular ring 11 depending therefrom guided in its reciprocatory movements by pedestal 12. A shaft 13 is caused to rotate by a motor 14 when connected thereto by clutch 15, causing eccentric cams 16 carried by shaft 13 to act upon the jolting 45 table.

A stripping plate, as 17, has projecting from one side near the margin a flange, as 18, forming a closed figure, its form being annular in the embodiment of the invention chosen for purposes of illustration.

Pedestals, as 19, eight being shown on the drawing, project from the stripping plate outside of the flange 18. An annular stripping ring 20 is provided with pedestals 21 adapted to register with and be supported by 60 pedestals 19. Ring 20 has perforated lugs, as 22, shown as two in number projecting in opposite directions from its margin.

Patterns are illustrated in Figs. 4 and 5, as at 23 and 24, each provided with an annular flange, as 25 and 26, adapted to rest upon flange 18, and each with a projection, as 27 and 28, adapted to rest upon ring 20. The patterns illustrated are for the production of a car wheel, but obviously other 70 shapes or forms might be submitted therefor. The pattern shown in place in the drag in Fig. 4 is formed to the shape of the inside of a car wheel and that of Fig. 5 to the outside of the same wheel.

A plurality of shafts, as 29, 30, shown as two in number, are journaled in bearings, as 31, and project through flange 18 and in the inclosed space cranks, as 32, 33, are rigidly secured to the shafts and connected by a 80 link 34. A lever 35 may be applied to one of the shafts, as 29, an end of the shaft being shown as projected beyond the base for the purpose. Each of the shafts has a cam, as 36, secured thereto near its end. A reciprocable pin, as 37, preferably provided with an antifriction roller such as 38, mounted in its end, is provided for each cam, and each pin stands within an opening in ring 20 and upon actuation of cam 36 will 90 be caused to project above the surface of this ring.

The drag has diametrically oppositely projecting lugs, as 39, perforated as shown, and the part of the flask for the cope is provided with a chill, as 40, and lugs, as 41, perforated as shown, project diametrically oppositely from the chill. When either the cope or the drag part of the flask with the appropriate pattern in place is to be filled 95 with sand on the jolting table, steady pins, as 42, are passed through the corresponding perforated lugs on the flask part and on ring 20 to maintain the relative position of parts. Also when the mold is completed and the 100 flask is assembled as shown in Fig. 9, steady pins are passed through corresponding lugs on cope and drag to position the parts.

Handling lugs, as 43, are shown as projecting from ring 20 whereby the ring and 110

pattern may be conveniently handled by a crane and similar lugs project from the chill for a like purpose.

Pattern 23 is shown as provided with projections, as 44, 45, and pattern 24 with a projection, as 46, to form core prints in the mold. The parts assembled as in Fig. 4, are placed on the jolter and filled with sand. In the case of the drag, ring 20 gives form 10 to the portion of the parting outside of the pattern, but the corresponding portion of the parting of the cope is formed by a portion of the chill. After the drag has been filled with sand and compacted, a board, as 15 47, Fig. 9, perforated for the escape of gases, is placed over the same. Lever 35 is now operated to cause pins 37, under influence of cams 36, to be projected above ring 20 against the edge of the drag whereby the 20 mold is gently and directly stripped from the pattern, by motion parallel with its axis. Pattern 24 is then substituted in place of pattern 23. The cope comprises an exterior ring, as 48, an interior ring, as 49, and radial ribs or webs, as 50. Ring 49 and ribs 50 are of such an extent as to be spaced away from the face of the pattern when assembled therewith in order that the face of the impression may be composed entirely of sand. 30 Also the lower edges of this ring and each rib are sharpened, as at 51, to prevent cavities in the sand of the finished mold opposite these edges. The provision of ring 49 and ribs 50 results in breaking up the sand into 35 small masses that may readily lift without danger of collapse of the mold.

The cope having been placed on ring 20 with the appropriate pattern in place, the gate forming implement 52 shown in Fig. 7, 40 is placed upon the core print 46 with the gate forming ribs 53 projecting downwardly about the same to the surface of the pattern. Sand is then placed in the cope and the jolter set in operation. A rammer, as 54, 45 described and claimed in an application filed by myself July 3, 1919, Serial No. 308,555, is placed on the sand in the cope to compact the same. This rammer comprises an annular weighting disk, as 55, having blocks 56 which may be of wood screwed thereto, as by screws 57. These blocks are 50 spaced apart to form spaces, as 58, which shall register with ribs 50 of the cope.

Under the influence of this weighted rammer and the jolting table the portion of the sand between the ribs will be compacted without hand ramming of each compartment. Fig. 5 shows the cope and its compacted sand separated from the pattern by 55 operation of lever 35. After the cope has been removed from the pattern, the gate forming implement 52 will be removed prior to assembly of the flask. When using the gate forming implement in the form disclosed, it is not necessary to be careful to

avoid getting sand in its interior. The dish may be filled with sand which will become compacted on the jolting machine so as to lift when implement 52 is removed.

An annular core, as 59, provided with supporting legs 60, which will register with and be located by core print 45, will be placed in the drag and chaplets 61 placed in openings in lugs 62 provided for the purpose on ring 49 are supplied to press upon core 59 and prevent the same from rising by flotation when the metal is poured in. Also a core 63 to provide for the shaft opening is placed in core print 44, and will project into the space, as 64, left by the removal of implement 52. 75 This will leave gates 65 communicating with the space in the mold to be filled with metal. If now metal be freely poured into space 64 upon the end of core 63 it will find ready access to the mold. Clamps, as 66, 80 are shown to hold the flask in assembled condition.

Obviously many changes and modifications can be made in the physical embodiment of my invention without departing 90 from the spirit thereof.

I claim as my invention:

1. In a mold forming apparatus, in combination, a base plate, a flange projecting from one face adjacent the periphery thereof adapted to support a pattern, a pair of shafts journaled on said plate and projecting through the flange, means to cause simultaneous motion of rotation of each shaft, a cam on each end of each shaft, a flask part 100 supporting ring supported above said base, pins adapted to reciprocate in openings in said ring, said pins coacting with said cams whereby motion of rotation of said shafts will cause the flask part and its contents to 105 be separated from the pattern.

2. In a mold forming apparatus, in combination, a base plate, an annular pattern supporting flange projecting from said plate, a plurality of pedestals projecting from the 110 plate outside of said flange, a flask part supporting ring provided with pedestals adapted to rest upon the first named pedestals and means to lift the flask part from the ring whereby the mold will be separated from the 115 pattern.

3. In a mold forming apparatus, in combination, a pattern supporting base plate, a frame supported on said base plate, adapted to underlie a portion of a pattern and to support a flask part and means carried by the base plate to separate the flask part from the pattern and frame.

4. In a mold forming apparatus, in combination, a base plate, means on said plate 125 for supporting a pattern, a frame supported on said plate in coacting relation with the pattern and adapted to support a flask part in molding relation with the pattern, and means acting through openings in the frame 130

to separate the flask part from the pattern and frame.

5. In a mold forming apparatus, in combination, a plate adapted to be placed on a jolting machine, means on the plate to support a pattern, a frame supported on the plate adapted to underlie a portion of the

pattern, to support a flask part in molding relation thereto and to give form to a portion of the mold, means carried by the plate 10 to separate the flask part from the frame and pattern.

DANIEL C. MULVIHILL.
